INVENTOR.

BY WALTER H. PLATH

Walter H. Plath

ATTORNEY.

UNITED STATES PATENT OFFICE

WALTER H. PLATH, OF TERRY, MONTANA

GRAIN-CAR DOOR

Application filed February 27, 1928. Serial No. 257,318.

My present invention, in its broad aspect, has reference to improvements in grain car doors of the type wherein a plurality of door sections, or planks, are used, and applied one section upon the next lowest therebeneath to raise the barrier or closure as the filling the car is completed. More particularly it is my purpose to provide a fastening device for closures of this character wherein means are provided for holding and rigidly retaining each section in place when it is set up. Another and equally important advantage of my device resides in the provision of means whereby the several fastening devices are concealed in the jamb of the door frame when the fastenings are not in use.

Other important objects of my invention may be briefly defined as follows: first, my fastening devices for the several sections of the door are simple in construction and can be made up in quantities and applied at small cost and without materially modifying conventional door jamb designs; second, each fastening is provided with a turn buckle for rigidly binding the door section in place; and in the modified form or alternate form, means are provided for making initial adjustments of the chains; and; third, my device can be readily applied without great cost as standard equipment upon grain cars now in use, and most of the parts thereof are standard articles which are sold on the open market.

While the foregoing distinguishing features and objects of my closure may be construed as the most apparent from the standpoint of general construction and arrangement of parts, other and equally important objects and advantages exist by virtue of the novel detailed construction of the separate elements thereof, and for this reason the above and other results and objects will be hereinafter more fully described in detail and specifically pointed out in the claims appended hereunto and forming a part of this specification.

In the accompanying drawings, wherein is illustrated the preferred and the alternative form of my invention;—

Figure 1 is a fragmentary, perspective view of a portion of my grain car door showing the devices applied thereto.

Figure 2 is a cross section through the lowermost section and a jamb,

Figure 3 shows two arrangements for nesting my fastening devices in the openings in the door jamb, and

Figure 4 is a detail view of my supplementary outlet device or closure in the lowest plank or section of the door.

Figure 5 is a fragmentary perspective view of an alternative form of my invention.

Figure 6 is a detail view of the plank fastenings in perspective,

Figures 7 and 8 are details of my chain and its connection with the jamb fitting and turnbuckle,

Figure 9 is a detail view of the socket connection for the turnbuckle hooks in the door sections.

In the drawings wherein like characters of reference are used to designate like or similar parts throughout the several views;—

The numeral (1) designates the side of a grain car, (2) the door jambs surrounding the opening (3), and (4) designates the sill. My closure is formed by utilizing a plurality of door sections or planks (5) which are backed against the inner face of the jambs (2) and arranged one above the others to effect a closure which is progressively built up as the car is filled with grain.

The respective jambs (2) are each notched out as at (6) adjacent each section (5), and retained in the notched out portions (6) are fastening devices generally designated by (7). Each fastening device (7) is formed with a sectional shank (8), the ends of which are screw threaded and secured in a turnbuckle (9). One section is formed with a hook (10) on its free end and the other with an eye (11). The fasteners (7) are arranged in pairs in the notches one above the other, and are swingably mounted by pins or bolts (12) extending through the jambs and notched out portions. They are usually staggered as shown in views A and B of Figure 3, and longer fastening devices may be nested after the manner shown in view B of Figure 100

3, that is by bringing the pins or bolts (12) closer together. When not in use the fastening devices are nested in the notches.

5 Eye bolts (13) are provided in each plank in which the hooked ends (10) of the fastening devices are engaged when the sections are set up, at which time the turnbuckles (9) are adjusted to rigidly retain the sections in place.

10 The lowermost section of the door is provided with an opening (14) adjacent to which, and on the inner side of the section and parallel to each other above and below the opening are U-bars (15) retained in place by bolts (16), and which constitute tracks for the closure (17). Stops formed of L-shaped brackets (18) limit the movement of closure (17) in either direction.

15 In Figures 5 to 9 I show an equally important and advantageous form of my invention which contemplates the provision of a hook device (19) in each jamb notch (6). Receivable in the hooks (19) are the links (20) of chains (21) and each link is reduced as at 20 (22) so that any one of the links may be engaged in the hooks to lengthen or shorten the chain. Each chain has a turnbuckle (23) the hooked end (24) of which engages in the opening (25) of a fitting (26) set into recesses in the grain boards to lie flush with the surface thereof. While this form of my invention is slightly more complicated than the alternative form heretofore described there are certain situations in which it must be 25 used. It is believed that the operation of my invention will be apparent from the foregoing, but it is especially pointed out that my door and the fastenings therefore may be readily and cheaply applied to types of grain doors now in use, and that it is simple in construction and can be manufactured at small cost.

30 While in the foregoing there has been illustrated and described such combination and arrangement of elements as constitute the preferred embodiments of my invention, it is nevertheless desired to emphasize the fact that interpretation of the invention should only be conclusive when made in the light of 35 the subjoined claims.

I claim:

1. In a fastener for grain car doors of the type having a plurality of superposed sections forming the closure, a plurality of sets of 40 fastening devices, one for each end of each section of the closure, the fastenings of each set being arranged one above the other and pivotally mounted in the jambs to swing to positions of concealment alongside each other 45 in a slot in the jamb provided for each set.

50 2. In a fastener for grain car doors of the type having a plurality of superposed sections forming the closure, a plurality of sets of fastening devices, one set for each end of each 55 section of the closure, the fastenings of each

set being extensible and arranged one above the other and mounted for both pivoting and sliding movement in the jambs to swing to positions of concealment side by side in nested relation in a slot in the jamb provided for each set, the jamb slot for each set being of a length greater than the length of any one fastener when extended.

5 3. In a fastener for grain car doors of the type having a plurality of superposed sections forming the closure, a plurality of sets of fastening devices, one set for each end of each section of the closure, the fastenings of each set being extensible and having linked extensions for selective engagement with an attaching device in the jamb, said fastenings of each set being arranged one above the other for swinging movement to positions of concealment side by side in nested relation in a slot in the jamb provided for each set, the jamb slot for each set being of a length greater than the length of any one fastener when extended, and none of the jamb slots being communicative with each other.

80 4. In a fastener for grain car doors of the type having a plurality of superposed sections forming the closure, a plurality of sets of fastening devices, one set for each end of each section of the closure, and each fastener engaging the section at an angle to the face of the jamb and the face of the section, the fastenings of each set being extensible and arranged one above the other and mounted for both pivoting and sliding movement in the jambs to swing to positions of concealment 85 side by side in nested relation in a slot in the jamb provided for each set, the jamb slot for each set being of a length greater than the length of any one fastener when extended, and there being no communication between 90 the slots.

95 In testimony whereof, I affix my signature hereunto.

WALTER H. PLATH.
